DESIGN.

C. ROHLFS.

HEATING STOVE.

No. 17,000.

Patented Nov. 23, 1886.

UNITED STATES PATENT OFFICE.

CHARLES ROHLFS, OF BROOKLYN, ASSIGNOR TO JOSIAH JEWETT, OF BUFFALO, NEW YORK.

DESIGN FOR A HEATING-STOVE.

SPECIFICATION forming part of Design No. 17,000, dated November 23, 1886.

Application filed August 24, 1886. Serial No. 211,769. Term of patent 14 years.

To all whom it may concern:

Be it known that I, CHARLES ROHLFS, of Brooklyn, in the county of Kings and State of New York, have invented a new and original

5 Design for Stoves, of which the following is a full, clear, and exact description.

Reference is to be had to the accompanying photograph of my newly-designed stove.

The leading features of my design consist in 10 a stork or other bird perched at the corners of the stove; in shaping the bird with outstretched wings; in representing the bird as holding a ball in its beak next to its breast, the ball supporting a raising; in the corner 15 columns on which the bird is perched; and, finally, in the general form, ornamentation of the castings of the stove, and in a Japanese figure at the top.

A represents the corner columns of the stove, 20 semi-tubular in form, and ornamented as shown in the accompanying photograph. Between the corner columns, A, are the side castings, B, ornamented as shown in the accompanying photograph, and curved to join the corner 25 columns, A, forming an angle made by a curve of a large radius joining a curve of small radius. The base C of the stove is substantially square, and ornamented as shown in the accompanying photograph, and the top D is ornamented as shown, and surmounted with a 30 Japanese female figure, E, standing upon a pedestal, F. The figure is represented with outstretched hands, in one of which is a fan. Upon the columns A is the figure of a bird, 35 G, with outstretched wings g g, and holding a ball, h, in its beak. The bird is represented

as standing upon a globe, i. Its neck is curved to hold the ball h near its breast. The wings g rest upon the rails H, which join the ball h in the bird's beak. 40

I claim—

1. In a design for a stove, the corner columns appearing at the angles of the side panels, and showing a bird in relief at the upper ends of the columns, substantially as shown 45 and described.

2. In a design for a stove, the corner columns, A, appearing at the angles formed by the side panels, B, and showing at the upper ends of the columns a bird in relief with outstretched wings appearing at the front of the panels, substantially as shown and described. 50

3. In a design for a stove, the corner columns, A, appearing at the angle formed by the side panels, B, and showing at the upper 55 ends of the columns a bird in relief joined at the beak by the side curves, H, substantially as shown and described.

4. In a design for a stove, a corner relief ornamentation in the form of a bird showing 60 outstretched wings, and showing a ball at the beak of the bird, substantially as shown and described.

5. The design herein shown and described for the corner-posts A of a stove, the same 65 consisting of the ball i and stork G, with outstretched wings, curved neck, and ball in its beak, joined by curves H.

CHARLES ROHLFS.
